UNITED STATES PATENT OFFICE.

EZRA L. GRIFFIN, OF DESLACS, NORTH DAKOTA.

SHOCK-LOADER.

No. 896,635.

Specification of Letters Patent.

Patented Aug. 18, 1908.

Application filed October 30, 1906. Serial No. 841,827.

To all whom it may concern:

Be it known that I, EZRA L. GRIFFIN, a citizen of the United States, residing at Deslacs, in the county of Ward and State of North Dakota, have invented new and useful Improvements in Shock-Loaders, of which the following is a specification.

The object of my invention is to provide a shock loader of simple, durable and inexpensive construction of the class designed to be advanced over a field by draft animals and to pick up shocks of small grain and convey them upwardly and laterally to dispose them in a wagon advancing on one side of shock loader.

A further object is to provide improved and simplified means for gathering shocks upon the main conveyer and to prevent the slats of said conveyer from becoming broken or the conveyer from becoming torn when it engages fixed objects in the path of the machine, and also to provide a gathering device upon which grain, grasses and the like will not become wound.

25 A further object is to provide an improved lateral conveyer frame capable of being quickly and easily tilted to discharge to either side of machine.

My invention consists in the construction, arrangement and combination of the various parts or elements of the shock loader whereby the objects contemplated are obtained, as hereinafter more fully set forth and pointed out in my claims and illustrations in the accompanying drawings in which,

Figure 1 shows a top or plan view of the complete machine embodying my invention. Fig. 2 shows rear elevation of same and the dotted lines indicate an adjusted position of the lateral conveyer. Fig. 3 shows a side elevation of the complete machine embodying my invention. Fig. 4 shows an enlarged detail sectional view of the compensating gear for transmitting power from the traction wheels to the longitudinal conveyer, and, Fig. 5 shows an enlarged detail view of the outer end of one of the supporting arms for the draft device.

Referring to the accompanying drawing I have used the numeral 10 to indicate the main frame of the machine. The forward end of the frame is supported upon two vertical shafts 11 slidably, rotatably mounted in the main frame, and having the supporting wheels 12 at their lower ends. The rear of the main frame is supported upon the axle

13 to which the traction wheels 14 are fixed. At the rear of the main frame is a superstructure 15 upon which the rear end of the longitudinal conveyer and the lateral conveyer are supported.

I have provided for advancing and steering the frame as follows: Fixed to the sides of the main frame near its forward ends are arms 16, which extend laterally and are provided at outer end with the pulleys 17, and rope or cable 18 is passed around the outer sides of said pulleys and in the rear of a pulley 19 which latter pulley is fixed to the main frame under its central portion. Attached to the forward ends of said rope or cable are the whiffle-trees 20 to which draft animals may be attached. Fixed to each of the upright shafts 11 is a lever 21, and these levers are connected by the cross piece 22 so that both of the forward wheels are held thereby in parallel position. For steering these forward wheels I have provided a vertical shaft 23 in the arm 16 at the right side of the frame. On the lower end of said shaft I have fixed a pair of thills 24 to receive the draft animal that is connected to the whiffle-tree at the right side of the machine. Near the power end of the shaft 23 is a sprocket wheel 25 having a sprocket chain 26 passed around it, having its ends attached to the ends of the cross piece 22 so that by turning the thill 24 to either side the supporting wheels 12 will be turned in a similar manner. If desired the thills 24 may be dispensed with, and the steering wheels controlled by the operator as follows: The numeral 27 indicates operator's seat mounted adjacent to right side of machine frame. Near the driver's seat is an upright shaft 28 provided with a crank 29 at its top, and connected by sprocket chain 30 with a sprocket wheel 31 on the shaft 23. In this way the driver may by manipulating crank 29 control the positions by the steering wheel 12.

The longitudinal conveyer comprises sides 32 and a slatted bottom 33, said frame being fixed at its rear end to the superstructure 15 and at its forward end to the frame 10. Said forward end, however, projecting some distance below the main frame and slightly in advance of the steering wheels. The conveyer apron is composed of chains 34 and cross slats 35 of the ordinary kind. Said apron being driven from a shaft 36 at the rear of the conveyer frame having sprocket wheels thereon to receive the chains 34. At

the forward lower corner of the sides 32 is a shaft 37 having thereon sprocket wheels to receive the chains 34 and also having between the sprocket wheels a cylindrical roller 38 of the diameter slightly less than that of the adjacent sprocket wheels. Said roller performs an important function in the operation of my invention in that the cross slats 35 lie close to it as they travel around it and therefore if any cross slat should strike upon a fixed object it will bend back and engage the roller, and be protected by the roller against breakage. Furthermore by having said cross slats run close to the said roller 15 grains and grasses and the like are prevented from entering between the slats and roller and winding around the roller. In this way a very objectionable feature in machines of this class is obviated.

20 I have provided means for adjusting the forward end of the machine frame relative to the steering wheels as required to raise and lower the forward end of the longitudinal conveyer as follows: Mounted in the machine frame is a transverse shaft 39 having on one end a lever 40 and on its other end a crank arm 41. Attached to said lever and crank arm is a rope or cable 42 passed over pulleys 43 on the upright shafts 11 and connected with the forward end of the conveyer's sides 32 and pawl 44 is connected to the lever 40 to engage a sector 45 on the frame. Obviously by manipulating the lever 40 the forward end of the frame may be vertically adjusted and it may be held in any position of its adjustments by the pawl and sector.

25 I have provided for driving the longitudinal conveyer apron as follows: Fixed to the rear axle 13 at each end is a traction wheel adjacent to which traction wheel is a sprocket wheel 46. Above the sprocket wheels is a shaft 47 having on each end a sprocket wheel 48. The wheels 46 and 48 each have a sprocket chain 49 passed 30 around them and also passed around a sprocket wheel 50 adjustably mounted on the frame 10 in front of the traction wheels, the under portions of said chains engaging the sprocket wheels 46 thus imparting motion to the shaft 47 in the proper direction. 35 In this connection it is to be noted that in turning around corners one traction wheel will move faster than the others and hence it will be impracticable to firmly fix both sprocket wheels 48 to the shaft 47. I have therefore provided a compensating gear device as on the shaft 47 as follows: As shown in the accompanying drawing this compensating gear device is located on the left end 40 of the shaft 47. The sprocket 48 being fixed to a hub 51, which hub is rotatably mounted on the shaft 47 and is provided with a beveled gear wheel 52. Spaced apart from the beveled gear wheel 52 is a similar beveled gear wheel 53 connected with a hub 54 fixed

to the shaft 47. Between the beveled gear wheels 52 and 53 is a loose collar 58, on the shaft 47 having beveled pinions 59 connected therewith and in mesh with the beveled sprocket wheels 52 and 53. The shafts on which the beveled pinions 59 are mounted are also used as supports for a sprocket rim 60. By this arrangement it is obvious that either one of the traction wheels may be moved faster than the other and yet both will serve to impart motion to the sprocket rim 60 in a uniform way in the well known manner in which compensating gear devices operate. A sprocket chain 61 is passed around the sprocket rim 60 and around a sprocket wheel 62 on the shaft 36 so that the apron of the longitudinal conveyer will be driven upon the advancing of the shock loader.

20 Mounted upon the superstructure at the rear of the main frame are the bearings 63 in which the shaft 64 is mounted in a position extended longitudinally of the main frame above its center. This lateral conveyer frame comprises sides 65 and a solid bottom 66. I have provided means for tilting the lateral conveyer frame as follows: Mounted near the rear of the main frame is a shaft 67 having on one end a worm wheel 68 in mesh with a worm 69 on a shaft 70 which shaft is provided with a crank 71 arranged adjacent to the driver's seat. On one side of the center of the shaft 67 a rope or cable 72 is fixed and wound. The said rope is extended straight upwardly and attached to the lateral conveyer frame, and on the opposite side of the center of the shaft 67 is a similar rope or cable 73 fixed to the shaft and wound thereon in an opposite direction; its upper end being attached to the lateral conveyer frame. By this arrangement of parts the operator upon turning the crank 71 will rotate shaft 67 thus causing one of the ropes thereon to be wound upon the shaft and the other to be unwound the corresponding distance. The worm gears in this connection serve to hold shaft 67 in any position of its adjustments and thus retaining the conveyer frame at any angle within its limit of movement. At the ends of the lateral conveyer frame are the shafts 74 having thereon the sprocket wheels 75 over which the sprocket chains 78 are passed. These sprocket chains are provided with cross slats 79 to frame and hold conveyer apron. This apron is driven as follows: On the shaft 64 are two sprocket wheels 80, only one of which is shown, which sprocket wheels are in engagement with the chains 78. On the forward end of the shaft 64 is a sprocket wheel 81 connected by a chain 82 with a sprocket wheel 83 on a short shaft fixed to the side of the longitudinal conveyer frame. On the same shaft is a beveled pinion 84 slidably mounted upon the shaft 36 of the longitudinal conveyer is a sleeve 130

having two beveled pinions 86 spaced apart and designed to be brought successively into mesh with the pinion 82. By having said sleeve 85 moved longitudinally on the shaft 5 36 the said sleeve is controlled as follows: On the side of the longitudinal conveyer frame is a brake 87 to which a bell-crank-lever 88 is fulcrumed one end thereof being connected with the sleeve 85 and the other end with a rod 90, which rod is pivoted to a lever 91 on the main frame adjacent to the driver's seat which lever is provided with a pawl 92 to engage a sector 93.

In practical use the shock loader is advanced over a field by draft animals and if the thills are provided for one of them the machine is steered by the animal hitched in the thills. If the thills are not provided the machine may be steered by the operator manipulating the steering crank. When in use the forward end of the longitudinal conveyer is adjusted to a side position that the roller therein will stand close to the ground surface. When the forward end of the longitudinal 25 conveyer strikes a shock of grain it will cause the shock to tilt rearwardly upon the conveyer apron and the upwardly moving slats thereof will carry the bundles of the shock upwardly and rearwardly. The roller at the forward end of the conveyer serves to protect the slats as before described. Assuming that there is no wagon at hand into which the bundles of grain may be discharged the operator swings the lateral frame to a substantially horizontal position and manipulates the lever 91 to throw both beveled pinions 86 out of mesh with the pinion 84 so that the lateral conveyer stands in-operative while the forward conveyer delivers the bundles thereto, then when a wagon is driven under the rear conveyer the apron thereof is started to move in the proper direction and the bundles will be delivered into the wagon. As the height of the load in the wagon increases the rear of the frame is tilted by the operator and elevated to suit the requirements.

Having thus described my invention, what I claim and desire to secure by Letters Patent of the United States, therefor is—

1. In a shock loader, the combination of a frame, supporting wheels therefor, a forwardly and downwardly inclined conveyer frame mounted in the main frame with its lower end capable of running close to the ground surface, a roller extended across the forward end of the frame, an endless conveyer comprising cross slats passed around said roller, and capable of engaging the ground over which the device is passing, said slats and roller being so arranged that the slats will lie flat against the roller throughout their entire length, to thereby prevent breakage of the slats when they strike obstructions 65 on the ground surface.

2. In a shock loader, the combination of a frame, supporting wheels therefor, a forwardly and downwardly inclined conveyer frame mounted in the main frame with its lower end capable of running close to the ground surface, a roller extended across the forward end of the frame, an endless conveyer comprising cross slats passed around said roller, and capable of engaging the ground over which the device is passing, said slats and roller being so arranged that the slats will lie flat against the roller throughout their entire length to thereby prevent breakage of the slats when they strike obstructions on the ground surface, and means for vertically adjusting the lower end of the conveyer frame.

3. In a device of the class described, the combination of a main frame, supporting wheels therefor, a forwardly and downwardly inclined conveyer frame mounted in the main frame with its lower end close to the ground surface, and its upper end pivotally supported, a roller in the lower end of the said conveyer frame, a slatted conveyer 90 passed around said roller, the slats thereof designed to run close to the ground surface and to pick up articles thereon, said slats also arranged to lie flat against said roller to prevent their breakage, and a lateral conveyer 95 arranged on the frame with its central portion adjacent to the upper end of the first mentioned conveyer, and means for operating the lateral conveyer in either direction.

4. In a device of the class described, the combination of a main frame, supporting wheels therefor, a forwardly and downwardly inclined conveyer frame mounted in the main frame with its lower end close to the ground surface, and its upper end pivotally supported, a roller in the lower end of the said conveyer frame, a slatted conveyer passed around said roller, the slats thereof designed to run close to the ground surface and pick up articles thereon, said slats also arranged 105 to lie flat against said roller to prevent their breakage, and a lateral conveyer arranged on the frame with its central portion adjacent to the upper end of the first mentioned conveyer, and means for operating the lateral 110 conveyer in either direction, and means for driving both conveyers by power from a supporting wheel.

5. In a device of the class described, the combination of a main frame, supporting 120 wheels therefor, a forwardly and downwardly inclined conveyer frame mounted in the main frame with its lower end close to the ground surface, and its upper end pivotally supported, a roller in the lower end of the said 125 conveyer frame, a slatted conveyer passed around said roller, the slats thereof designed to run close to the ground surface and pick up articles thereon, said slats also arranged to lie flat against said roller to prevent their break- 130

age, and a lateral conveyer arranged on the frame with its central portion adjacent to the upper end of the first mentioned conveyer, and means for operating the lateral conveyer 5 in either direction, and means for vertically adjusting the lower end of the main conveyer frame.

6. In a device of the class described, the combination of a main frame, supporting 10 wheels therefor, a forwardly and downwardly inclined conveyer frame mounted in the main frame with its lower end close to the ground surface, and its upper end pivotally supported, a roller in the lower end of the said 15 conveyer frame, a slatted conveyer passed around said roller, the slats thereof designed to run close to the ground surface and pick up articles thereon, said slats also arranged to lie

flat against said roller to prevent their break age, and a lateral conveyer arranged on the 20 frame with its central portion adjacent to the upper end of the first mentioned conveyer, and means for operating the lateral conveyer 25 in either direction, and means for vertically adjusting the lower end of the main conveyer frame, said means comprising a cable fixed to the lower end of the main conveyer frame, an elevated pulley having said cable passed over it, a lever fulcrumed to the main frame and having said cable attached to it, and means 30 for locking said lever in various positions.
